UNITED STATES PATENT OFFICE

2,292,682

HEATING OF FLUID

Marion W. Barnes, Chicago, Ill., assignor to Universal Oil Products Company, Chicago, Ill., a corporation of Delaware

Application February 10, 1941, Serial No. 378,138

9 Claims. (Cl. 122—356)

This invention is directed to an improved form of heater wherein separate streams of fluid may be quickly heated under substantially uniform conditions. It is particularly well adapted to heating hydrocarbons in liquid, vaporous or gaseous state to the relatively high temperatures required for their thermal or catalytic conversion, but is not limited to the treatment of any particular type of fluid.

The heater provided is of the combination radiant and convection type and its structural form is similar to that disclosed in my United States Patent No. 2,212,002, issued August 20, 1940, the essential difference being in the form of fluid conduit provided and the flow of fluid therethrough. The heater provided by the present invention therefore retains the advantages of that disclosed in the aforementioned patent in so far as its general structural form is concerned and provides additional advantages in quickly heating fluids to relatively high temperatures with low pressure-drop through the fluid conduit. Quick heating and low pressure drop through the heating coil are often important factors, particularly in thermal or catalytic conversion reactions which are advantageously conducted at high temperatures and low pressure.

The accompanying drawing diagrammatically illustrates one specific form of the heater provided by the invention. Its advantageous features will be apparent from the following description. Its distinction from the heater disclosed in the aforementioned patent will also be apparent by reference to the latter and comparison of the structure illustrated and described therein with that herein disclosed.

In the drawing Fig. 1 is a diagrammatic sectional elevation of the heater and Fig. 2 is a diagrammatic section taken along the plane indicated by line 2—2 in Fig. 1.

Referring to the drawing, the outer walls of the furnace comprise side walls 1 and 2, a roof 3, the interior surface of which is preferably curved, as illustrated, a floor 4 and end walls not illustrated in this particular view.

The interior of the furnace is divided by bridge wall 5 into a combustion and radiant heating compartment 6 and a fluid heating compartment 7. The bridge wall extends between the end walls of the furnace from the floor to a level substantially beneath the roof, leaving a space above the bridge wall for the free and unrestricted passage of combustion gases from zone 6 to zone 7.

The bridge wall 5 may be built up solid of refractory shapes or, as in the case here illustrated,

may comprise two spaced refractory walls 8 and 9, which are preferably of suitable refractory shapes suspended from a suitable steel or other metal structure, not illustrated, disposed in space 5 10 provided between walls 8 and 9.

The fluid conduit or heating coil provided comprises a plurality of substantially parallel bent or U-shaped tubular elements 11 disposed adjacent bridge wall 5 and each extending from a manifold or header 12 adjacent the floor of combustion and heating zone 6 to another manifold or header 13 disposed within fluid heating zone 7 adjacent the bridge wall.

Another portion of the fluid conduit is disposed substantially entirely within fluid heating zone 7 and comprises a plurality of substantially parallel tubular elements 14, each having a number of superimposed and interconnected U-shaped sections and each extending from a manifold or header 15 which, in this instance, is disposed outside the furnace structure adjacent the lower portion of wall 2 to the aforementioned manifold or header 13 with which tubes 11 are also connected.

25 As illustrated in Fig. 2, the U-shaped sections of each of the tubular elements 14 are disposed angularly with respect to the adjoining U-shaped sections so that the horizontal straight sections of tubes in each horizontal row of the bank comprising tubes 14 are disposed in staggered relation to those in the adjacent horizontal row. This arrangement gives better contact of the combustion gases passing through zone 7 with the tubular elements 14, but is not to be construed as a limitation since the sections of each tube 14 may, when desired, be arranged in the same vertical plane.

Assuming that the flow of fluid undergoing heat treatment is first through tubes 14 and then through tubes 11, it is supplied by any suitable well known means, not illustrated, through line 16 to manifold 15 and flows therefrom as a plurality of separate streams of substantially equal volume through tubular elements 14 in a general upward direction into manifold 13. From manifold 13 the fluid flows as a plurality of separate streams of substantially equal volume through tubular elements 11, first in an upward direction through the portion thereof disposed in fluid heating zone 7 and then in a downward direction through that portion thereof disposed in combustion and heating zone 6, to manifold 12 wherefrom the heated fluid is discharged as a single stream through line 17 to any desired destination.

Fuel, preferably in gaseous or liquid form and, in the latter case, in well atomized or finely divided state, is supplied to the lower portion of heating and combustion zone 6 by means of suitable burners 17 through firing ports 18 in floor 4. Regulated quantities of air for combustion and or stream for atomization of the fuel may be supplied to combustion zone 6 through the burners and additional quantities of air may be supplied to burner compartment 19 by regulation of a suitable damper or the like 20 and drawn into combustion zone 6 through burner ports 18 by the jet action of the burner.

Although only a single burner and burner port are shown in this particular view of the furnace, a plurality of each is preferably provided at intervals so spaced along the length of the furnace as to give a substantially continuous curtain of flame and hot combustion gases a short distance above the burner ports.

The opening through each burner port is preferably at a slight angle from the horizontal, as here illustrated, whereby the flames and hot combustion gases are caused to impinge on the refractory side wall 1 and flow upwardly thereover, whereby the wall is heated to a radiant condition and the hot gases are partially cooled by contact therewith.

Heat is transmitted from the refractory side wall 1, as well as from the flames and incandescent gases to one side of each of the tubular elements 11 and to the refractory wall 9, which latter, in turn, reflects heat to the opposite side of each of the tubular elements 11.

After leaving combustion and heating zone 6, the hot combustion gases travel over wall 5 and, due to their heated condition, the main stream of these gases is maintained in intimate contact with the surface of roof 3. The curvature of the roof maintains a relatively stream line flow of gases and helps to eliminate excessive localized cycling of the combustion gases (commonly termed parasitic circulation) in the upper portion of the furnace. The hot gases passing over the surface of roof 3 heat the same to a high temperature and radiant heat is transmitted therefrom as well as from the hot gases themselves to that portion of the tubular elements 11 located adjacent the upper portion of the bridge wall, the latter also serving to reflect heat to the opposite side of each of these tubes.

Depending upon the firing conditions employed and particularly upon the proportion of excess air utilized, the combustion gases having passed over bridge wall 6 from combustion and heating zone 6 to fluid heating zone 7 will retain a variable amount of radiant energy which is transmitted from the gases and from the refractory side wall 2 of the furnace to one side of that portion of each of the tubular elements 11 located in fluid heating zone 7 and to the adjacent surface of the bridge wall which, in turn, reflects heat to the adjacent side of these tubes.

The upper portions of each of the tubular elements 14 may, depending upon the firing conditions employed, also receive a considerable amount of radiant heat and these tubular elements 14 receive fluid heat along substantially their entire length from the combustion gases which pass downwardly about and in contact therewith. After their contact with the tubular elements 14, the resulting substantially cooled combustion gases are directed through flue 21 to stack 22 wherein draft is controlled by means of a suitable damper 23.

The entire furnace is mounted upon a suitable foundation, indicated at 24, and, preferably, the entire furnace, with the exception of the foundation, is disposed above the grade line, which is here indicated at 25, whereby underground structure is minimized and underground flues and ducts are entirely eliminated.

It will, of course, be understood that the invention is not limited to all of the specific details of construction above mentioned, since many modifications and minor departures therefrom, which are within the scope of its broader aspects, will be readily apparent to those familiar with the art. For example, headers or manifolds similar to manifold 13 may be interposed in tubes 11 as the upper end of the substantially straight sections thereof in zones 6 and 7, whereby only relatively short bent tube sections will be required over the top of the bridge wall to connect the manifolds. On the other hand, tubular elements 14 and 11 may be joined by substituting bends connecting the same in place of manifold 13. Manifold 15 may be disposed within rather than exterior to heating zone 7, when desired, or, when desired, manifold 12 may be disposed exterior to combustion and heating zone 6 instead of within this zone, as illustrated. Although, in the case here illustrated, tubes 11 and 14 are of substantially the same cross-sectional area, they may differ in size, when desired, and the number of tubes 11 employed does not necessarily correspond to the number of tubes 14. It is also entirely within the scope of the invention to pass the fluid being heated, first through tubes 11 and then through tubes 14, employing manifold 12 as the inlet header and manifold 15 as the outlet header.

The invention also contemplates, when desired, providing a plurality of inlet and outlet lines 40 communicating with the respective inlet and outlet headers to obtain better distribution of fluid through the individual parallel sections of the fluid conduit and, in such instances, when desired, the inlet and outlet manifolds may be divided by suitable partitions into a plurality of inlet and outlet compartments. In the latter case, any desired number of separate streams of different fluids may be separately heated and by varying the quantity of fuel and air supplied 45 through the independent burners, different firing conditions may be employed in different horizontal sections of zone 6 in order to obtain independently controlled heating conditions for each type of fluid supplied to the heater; particularly 50 in that portion of tubes 11 disposed within combustion and heating zone 6.

I claim as my invention:

1. A heater for fluids comprising, in combination, refractory exterior walls defining a combustion chamber and a fluid heating chamber separated by a refractory interior wall, means for directing hot gases resulting from the combustion of fuel through the combustion chamber in contact with the surface of the exterior wall facing said interior wall and from the combustion chamber into and through the fluid heating chamber, a fluid conduit comprising a plurality of tubular elements connected for substantially horizontal parallel flow of separate streams of fluid therethrough disposed in the direct path of travel of the combustion gases passing through said fluid heating chamber, and another fluid conduit comprising a plurality of tubular elements connected for substantially vertical parallel flow of separate streams of fluid therethrough and disposed

in the combustion chamber adjacent the surface of said interior wall.

2. A heater for fluids comprising, in combination, refractory exterior walls defining a combustion chamber and a fluid heating chamber separated by a refractory interior wall, means for directing hot gases resulting from the combustion of fuel through the combustion chamber in contact with the surface of the exterior wall facing said interior wall and from the combustion chamber into and through the fluid heating chamber, a fluid conduit comprising a plurality of tubular elements connected for substantially horizontal parallel flow of separate streams of fluid therethrough disposed in the direct path of travel of the combustion gases passing through said fluid heating chamber, and another fluid conduit comprising a plurality of tubular elements connected for substantially vertical parallel flow of separate streams of fluid therethrough and disposed in the combustion chamber adjacent the surface of said interior wall, the first and second named conduits being connected for the flow of fluid therethrough in series.

3. The heater defined in claim 1, having its parts so arranged and constructed that said hot gases pass in a general vertical direction through the combustion chamber and through the fluid heating chamber with reverse flow in each of said chambers as compared with the other.

4. The heater defined in claim 2, having its parts so arranged and constructed that the fluid undergoing heating passes through said fluid conduits in a general direction countercurrent to that of the combustion gases from which they receive heat.

5. The heater defined in claim 2, having its parts so arranged and constructed that the fluid undergoing heating passes through said fluid conduits in a general direction concurrent to that of the combustion gases from which they receive heat.

6. A heater for fluids comprising, in combination, refractory side walls, end walls, a roof and a floor, a refractory bridge wall within the heater extending between said end walls from the floor to a level substantially beneath the roof and dividing the interior of the heater into a combustion chamber and a fluid heating chamber, means for directing fuel and air upwardly into the combustion chamber toward the surface of the refractory side wall thereof facing said central wall, means for directing hot combustion gases resulting from the combustion of said fuel upwardly through the combustion zone in contact with said side wall and over the central wall in contact with the roof into and through the fluid heating chamber, a plurality of tubular fluid conduits connected for the parallel flow of sepa-

rate streams of fluid therethrough disposed in the direct path of travel of the combustion gases passing through the fluid heating chamber, and a plurality of tubular fluid conduits connected for the parallel flow of separate streams of fluid therethrough disposed adjacent the bridge wall and extending from adjacent the floor in the combustion chamber over the bridge wall into the fluid heating chamber, the first and last named conduits being connected for the flow of fluid therethrough in series.

7. The heater defined in claim 6, wherein each of said tubular fluid conduits in the fluid heating zone comprises a plurality of substantially parallel straight sections connected in series by return bends, each of said conduits being connected at one end with a common manifold and these conduits communicating at their opposite ends with the conduits adjacent the bridge wall.

8. The heater defined in claim 6, wherein each of said tubular fluid conduits disposed adjacent the bridge wall comprises substantially vertical straight sections disposed on opposite sides of the bridge wall and connected over the top of the latter by return bends.

9. A heater for fluids comprising, in combination, refractory side walls, end walls, an arched roof and a floor, a refractory bridge wall within the heater extending between said end walls from the floor to a level substantially beneath the roof and dividing the interior of the heater into a combustion chamber and a fluid heating chamber, means for directing a combustible fuel air mixture into the combustion compartment toward the surface of the refractory side wall thereof facing the bridge wall, means for directing resulting hot combustion gases upwardly through the combustion chamber in contact with said side wall and over the bridge wall in contact with said arched roof into and through the fluid heating chamber, a plurality of tubular fluid conduits connected for the parallel flow of separate streams of fluid therethrough disposed in the direct path of travel of the combustion gases passing through the fluid heating chamber, each of said conduits being substantially vertically disposed and comprising a plurality of substantially horizontal sections connected in series by return bends, and a plurality of tubular fluid conduits connected for the parallel flow of separate streams of fluid therethrough and disposed adjacent the bridge wall, each of the last named conduits extending from adjacent the floor in the combustion chamber over the bridge wall into the fluid heating chamber, the first and last named conduits being connected for the flow of fluid therethrough in series.

MARION W. BARNES.
